WRINGER ROLL DRIVE MECHANISM

Nicholas L. Etten, Waterloo, Iowa, assignor to
Chamberlain Corporation, Waterloo, Iowa

Application June 5, 1935, Serial No. 25,039

3 Claims. (Cl. 68—253)

This invention has reference to wringer roll drive mechanism and has for one of its objects to provide a mechanism disposed within a wringer roll operable to establish driving connection 5 between the roll and a prime mover in accordance with conditions under which the roll is operated.

Another object is to provide a clutching mechanism disposed within a wringer roll, which is operable to establish driving connection between the roll and a prime mover when the roll is held under normal working pressure and is rendered inoperative for the purpose when pressure on the roll is relieved.

15 A further object lies in the provision of a roll wringer mechanism including a pair of rolls, one of which is adapted to be pressed against the other, and mechanism for bringing about such pressure or relieving the same, wherein one of 20 the rolls is provided with a clutching mechanism, disposed within itself, which is operable to automatically establish driving connection between the roll and a prime mover when the roll is pressed and is automatically rendered inoperative 25 when the pressure is relieved.

Other objects will appear in the following description and accompanying drawing in which;

30 Fig. 1 is a side elevational view showing a roll wringer mechanism embodying my invention with portions of the frame broken away to expose interior parts;

Fig. 2 is a broken sectional view, taken at approximately the center line of one of the rolls, showing details of mechanism to be explained;

35 Fig. 3 is a fragmental view, partly in section, showing details of mechanism, the same being taken on line 3—3 in Fig. 2;

Fig. 4 is a view similar to Fig. 3 showing parts in operated position as will be described; and

40 Fig. 5 is a sectional view taken on line 5—5 in Fig. 2.

45 For the purpose of illustration I show and describe a roll wringer mechanism of somewhat conventional type. It is to be understood that my invention is not limited to application to any particular type or make of wringer.

The mechanism includes a lower frame portion 10, provided with upright portions 11 and 12 which carry lugs 13 and 14 near their upper ends.

50 Upon the upright portions is disposed a top frame member 15 which is provided, at the right hand end, with a hook portion 16 adapted to engage lug 13 in such a manner as to prevent the top frame from moving away from upright 12.

55 At the left hand end, top frame 15 carries a

hand lever 17 pivotally attached to the top frame by means of a pin 18.

The upper arm of the lever lies in an angular relation to the top frame and is normally urged toward this position by a spring 19. The lower 5 arm 20 has an inwardly directed hook 21 adapted to engage lug 14 when the upper arm of lever 17 lies in elevated position.

Hook 21 is obviously adapted to prevent movement of the top frame away from upright 11. 10

It will be apparent that hooks 16 and 21 cooperate to hold the top frame in position on the uprights so that the left hand end of the top frame may be released by manipulation of lever 17 downwardly into the position indicated in 15 dotted lines, to remove hook 21 from lug 14.

Upper and lower rolls 22 and 23 are disposed in the lower frame structure.

The lower roll is supported by means of its 20 shaft ends 24 and 25 being journalled in bearing blocks 26 and 27 stationarily supported in the lower frame structure.

Upper roll 22 rests upon the lower roll and its 25 shaft 28 supports inverted bearing blocks 29 and 30 which in turn support opposite ends of a spring 31. The spring is supported in the top frame by means of attachment to a screw member 32 which is threadedly mounted in the top frame.

With the top frame locked upon uprights 11 30 and 12 as explained, the screw 32 may be adjusted to stress the spring 31 downwardly to press the upper roll 22 against the lower roll whereby the mechanism is made ready for usual wringing operation.

35 With the parts in this position, when it is desired to quickly release the pressure of the rolls, it is but necessary to manipulate the lever 17 downwardly toward the dotted line position whereupon the hook 21 disengages from lug 14 40 and the left hand end of the frame is made free to move upwardly in response to the pressure of spring 31.

This movement of the left hand end tends to cause unhooking of the right hand end, and the 45 top frame is thus made movable upwardly to permit complete relaxation of the spring and removal of pressure between the rolls.

My invention is principally directed to the 50 mechanism of the lower roll 23, which operates responsively to the pressure on the rolls, as will now be explained:

The lower roll mechanism comprises a metallic tubular member 33 which is surrounded by a pad or tube of rubber 34 by means of which it is given 55

the appearance and utility of a conventional wringer roll.

In each end of tube 33 there is affixed a plug, 34 and 35.

5 Journalled in plug 34 is the shaft 24 extending a considerable distance within the tube and carrying at its inner end a head portion 36 which is fitted for rotation in the tube. The shaft is confined against longitudinal movement toward 10 the left by means of an affixed collar 37 seated upon plug 34.

Shaft 25, at the opposite end of the roll, extends outwardly from the roll a sufficient distance to clear the outer wall of upright 12 and 15 to have means of connection, as at 38, with a power source not shown.

A contracted portion 39, of the shaft is journalled in plug 35 and extends within tube 33 as shown, to terminate in an enlarged head portion 20 40 fitted for rotation in the tube.

The inner end of shaft 24 is recessed and in the bottom of the recess there is affixed a torsionally flexible spring member 41, the opposite end of which is affixed in the head 40.

25 By means of the spring, shafts 24 and 25 are connected for operation in a novel manner as will be explained.

Figs. 2 and 3 illustrate that head 36 and plug 35 are provided with diametrically disposed 30 grooves 42 and 43 respectively, disposed in opposing relation, and that head 40 has a plurality of openings 44 lying parallel with the axial center of the shafts.

In the openings 44 there are loosely fitting balls 35 45 having a combined diameter equaling more than the width of head 40. The arrangement is illustrated in the several views.

Operation of the mechanism is as follows:

With the top frame released and spring 31 40 relaxed the pressure of roll 22 upon roll 23 is only that due to the weight of the roll and accessory parts.

With this as a basis, the spring 41 is made sufficiently stiff to overcome the friction developed on shaft 24 as a result of said weight, and to impart rotary movement of the driving shaft 25 to the shaft 24 without appreciable flexing.

In manufacture the spring 41 is attached in such position that groove 42 and openings 44 lie 50 in register as in Fig. 3. With the parts in this position and the load adjusted as above, shaft 25, together with shaft 24, may be rotated without accompanying movement of roll 23.

However, if the top frame is replaced and the 55 upper roll is placed in pressure relation with roll 23, friction on the bearing surfaces will be considerably increased and shaft 24 will thus require greater power to be transmitted through spring 41 in order to rotate it. This transmission of 60 greater power cannot be accomplished without a certain amount of distortion of the spring and such distortion results in a lagging movement of shaft 24 with respect to shaft 25, which places the parts in the relative position shown in Fig. 4, 65 wherein the balls have been forced out of groove 42 and positioned to engage groove 43 whereby head 40 is placed in keyed relation with roll 23 to drive the roll unitarily with shaft 25.

Under conditions of practical use, when garments are passed between the rolls the pressure 70 upon roll 23 is increased and this results in further distortion of spring 41, however when the spring is distorted sufficiently to place the flat face of head 36 opposite the balls 45, the latter 75 are abutted to firmly engage the plug 35. From

this point no further movement of head 40, with respect to head 36, is probable for the reason that the friction between shaft 24 and bearing 26, which resists rotative movement of the shaft and would tend to cause the shaft to lag, is at least equalled by the friction between plug 34 and the shaft, which would tend to carry the shaft in rotation with the roll.

It will be obvious that releasement of the top frame, as described, would instantly result in 10 replacement of the driving parts in original position to disable the driving connection and permit shafts 24 and 25 to continue rotation while roll 23 remains stationary.

In the above manner the rolls are automatically 15 driven or stopped in accordance with the pressure existing between the rolls.

Roll wringer mechanisms having means for releasing pressure between the rolls are well known. However, under conditions of practical 20 use the release mechanism is seldom used except in emergency, such as would appear when fingers are caught between the rolls, or hair or personal clothing are wrapped around them.

In the case of such emergency it is obviously 25 necessary to instantly relieve the pressure between the rolls but the danger of injury to an operator does not disappear upon mere release of the pressure. In the event of hair or clothing being wrapped around the rolls, and in numerous other possible situations, release of the pressure, with continuation of rotation of the rolls only lessens the danger but does not remove it.

In view of this it will be apparent that the 30 ideal arrangement would provide means for instantly relieving the roll pressure and simultaneously arresting rotation thereof, and it is to the end of providing an effective means of arresting rotation of the rolls simultaneously with release of pressure therebetween that I have produced the invention herein disclosed.

Modifications of structure are obviously possible without alteration of the principle involved. I do not wish to be limited in structure, function or application of the invention except within the 35 scope of the appended claims.

What I claim is:

1. In a roll wringer mechanism, a pair of co-operative rolls, instrumentalities for pressing said rolls together and for releasing the rolls from 50 pressing engagement, one of said rolls being hollow, bearings for said roll including a support at one end thereof and a drive shaft at the opposite end, and clutching means confined within said roll between said bearings operable by bearing 55 friction to rotate the rolls when pressed together and to stop rotation when the rolls are released from pressure.

2. In a roll wringer mechanism, a pair of co-operative rolls, instrumentalities for pressing said rolls together and for releasing the rolls from pressing engagement, one of said rolls being hollow and provided with bearing members at its opposite ends, a shaft rotatably mounted in the bearing at one end of said roll, a drive shaft 60 rotatably mounted in the bearing at the other end of said roll, clutching members confined within the interior of said roll, and interconnections between said drive shaft, clutching members, and rotatable shaft whereby bearing pressure 65 will automatically control the driving engagement and release of the roll.

3. In a roll wringer mechanism, a pair of co-operative rolls, instrumentalities for pressing said rolls together and for releasing the rolls from 70

pressing engagement, one of said rolls being hollow and provided with bearing members at its opposite ends, a shaft rotatably mounted in the bearing at one end of said roll, a drive shaft rotatably mounted in the bearing at the other end of said roll, clutching members confined within the interior of said roll, and interconnections between said drive shaft clutching members, and

rotatable shaft, said interconnections including a yieldable coupling between said shafts whereby they may rotate together when the roll is not clutched but may have relative rotation when influenced by bearing pressure to apply the clutching members to drive the roll from the interior thereof.

NICHOLAS L. ETTEL.
